Primary Examiner — Holly E Thurman(74) *Attorney, Agent, or Firm* — K&L Gates LLP(57) **CLAIM**

The ornamental design for an electronic device carrying case, as shown and described.

DESCRIPTION

FIG. 1 is a back view of an electronic device carrying case showing our new design, in which the case is shown on a smaller scale;

FIG. 2 is a perspective view thereof;

FIG. 3 is a back view thereof;

FIG. 4 is a front view thereof;

FIG. 5 is a first end view thereof;

FIG. 6 is a second end view thereof;

FIG. 7 is a first side view thereof; and,

FIG. 8 is a second side view thereof.

The unshaded surfaces that are visible through the openings and the broken lines on the unshaded surfaces depict an unclaimed electronic device. All other broken lines depict unclaimed portions of the electronic device carrying case and unclaimed environment and form no part of the claimed design.
